IRRIGATION PIPE COUPLING

James K. Campbell, Santa Clara, Calif., assignor to Food
Machinery and Chemical Corporation, San Jose, Calif.,
a corporation of Delaware

Application April 27, 1956, Serial No. 41,228

Term of patent 14 years

(Cl. D91—3)

FIG. 1

FIG. 2

FIG. 1

Fig. 1 is a perspective of an irrigation pipe coupling embodying my design, particularly showing the front and one side of the coupling.

Fig. 2 is a perspective of the coupling of Fig. 1, particularly showing the rear and the other side of the coupling.

Fig. 3 is a top plan view of the coupling.

I claim:

The ornamental design for an irrigation pipe coupling, as shown.
